United States Patent Office

Des. 212,369
Patented Oct. 8, 1968

212,369

HOLDER FOR SOAP, WASH CLOTHS, AND SIMILAR ARTICLES

Charles H. Hagopian, 2344 Davidson Ave.,
Bronx, N.Y. 10468

Filed Oct. 23, 1967, Ser. No. 9,128

Term of patent 14 years

(Cl. D33—26)

FIG. 1

FIG. 2

FIG. 3

FIG. 4

FIG. 5

FIG. 7

FIG. 6

FIG. 8

FIG. 9

FIG. 10

FIG. 1 is a front elevational view of a holder for soap, wash cloths and similar articles, showing my new design;

FIG. 2 is a side elevational view thereof;

FIG. 3 is a rear elevational view thereof;

FIG. 4 is a top plan view thereof;

FIG. 5 is a bottom plan view thereof;

FIG. 6 is a side elevational view of a modified form of the holder for soap, wash cloths, and similar articles shown in FIG. 1;

FIG. 7 is a front elevational view of FIG. 6;

FIG. 8 is a top plan view of FIG. 6;

FIG. 9 is a rear elevational view of FIG. 6;

FIG. 10 is a bottom plan view of FIG. 6.

I claim:

The ornamental design for a holder for soap, wash cloths, and similar articles, substantially as shown and described.
